Specification for Design.

Patented Feb. 16, 1915.

Application filed October 28, 1914. Serial No. 869,154. Term of patent 7 years.

To all whom it may concern:

Be it known that I, GEORGE L. LANG, a citizen of the United States, residing at Newark, county of Essex, State of New Jersey, have invented a new, original, and ornamental Design for a Distributer-Block, of which the following is a specification, reference being had to the accompanying drawing, forming a part thereof.

In the drawing wherein I have shown my new design, Figure 1 is a top plan view and Fig. 2 is a side elevation thereof.

I claim:

The ornamental design for a distributer block, as shown.

In testimony whereof, I affix my signature in the presence of two witnesses.

GEORGE L. LANG.
